DESIGN.

—o—

J. L. FOLSON.

CARPET.

No. 18,131.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,131, dated March 6, 1888.

Application filed January 26, 1888. Serial No. 262,054. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is composed of groups of conventionalized flower and leaf forms, some of the groups having fragments of coral-like or geometrical ornamentation on their borders. In 20 most of these groups there is a large central circular flower form made up of concentric rings of flower-leaves, the edges of these flower-

leaves being more or less regularly indented or scalloped. Around this central figure are gathered leaves and circular flower forms of 25 varying size and outline. Some of the larger leaves are curved into a scroll form and scalloped on their outer edges.

In one part of the design a large circular flower form is shown surrounded by a circle 30 or wreath of smaller gem-shaped flower forms. One group has at its center a large scroll-shaped leaf, with a border-work of short stems supporting gem-shaped flower forms, and with a large circular flower and leaves above. 35

What I claim as new, and desire to secure by Letters Patent, is—

The design for carpets, consisting of the design substantially as shown.

JAS. L. FOLSOM.
